UNITED STATES PATENT OFFICE.

JULIUS J. HOLLEY, OF HOLMEN, WISCONSIN.

DISH-WASHING MACHINE.

No. 926,744.

Specification of Letters Patent.

Patented July 6, 1909.

Application filed March 29, 1909. Serial No. 486,305.

To all whom it may concern:

Be it known that I, JULIUS J. HOLLEY, a citizen of the United States, residing at Holmen, in the county of La Crosse and State of Wisconsin, have invented a new and useful Dish-Washing Machine, of which the following is a specification.

My invention relates to dish washing machines, and the object is to provide a cheap, simple yet efficient machine for washing cups, saucers, plates and dishes without using so cold water that the hands can be put into it, as is required when washing dishes by hand.

In the accompanying drawing, Figure 1 is a top view of my improved dish washing machine. Fig. 2 is a vertical section on line *a—a* in Fig. 1. Fig. 3 is a horizontal section of the machine as on line *b—b* in Fig. 2, with the dishes in Fig. 2 omitted. Fig. 4 is a diametrical section on line *c—c* in Fig. 1 of the cover and top of the frame.

Referring to the drawing by reference numerals, 1 designates a tub having in its cover 2 a water inlet 3, and near its bottom a faucet 4 through which the water may be let out after the washing is done.

About an inch above the real bottom 5 of the tub is supported on props 6, a false bottom 7 having a series of circularly disposed slits 8 adapted to hold dishes and plates in the position indicated at 9 in Fig. 2. In the middle of the false bottom is an aperture large enough to receive and hold in position the lower end of a skeleton frame composed of a bottom piece 10, a top piece 11 and vertical side bars 12. The top piece 11 fills the central opening 13 in the cover and is provided with two opposite arms 14, which fit into notches 15 in the cover and have their ends 16 extended under the cover beyond the notches whereby the weight of the cover is imposed upon the frame.

Journalized in the bottom and top portion of the frame, and projecting above the latter, is a shaft 17, which by means of arms 18 carries a plurality of wings or fans 19, which together with the shaft form an agitator or dasher. The upper end of the shaft is further journalized in a bracket 20 fixed upon the top of the frame, and between said bracket and the frame top is fixed on the shaft a bevel pinion 21, which is rotated by a bevel gear 22, mounted by a stud on a short shaft

23 on the bracket and is turned by a crank 55 handle 24. To prevent the dishes from falling into the dasher upstanding guarding pins 25 are provided on the base portion of the frame, though they may also be provided upon the inner edge of the false bottom, as 60 shown at 26 in Fig. 2.

In the operation of the machine, the plates and dishes are placed in the position shown at 9 in Fig. 2, all around in the false bottom, the smallest plates being nearest the center 65 of the machine so as to permit the water to reach the larger plates farther away when the water is agitated. The hot water is poured in until the dishes are all fairly submerged; the frame is then put in place, the 70 cover adjusted and the crank is turned until the dishes are washed by the water forced in all directions by the wings of the dasher. The cover and frame are then removed and the dishes taken out and either wiped or permitted to dry from the heat they have received from the water. If the water is too 75 hot for putting the hands into it in removing the dishes the faucet may be opened to reduce the water sufficiently for the hands to 80 reach the dishes as they project above it. Or, if the same water is not to be used for another batch of dishes all the water may be run out before removing the dishes, or the 85 dishes may be left standing in the machine to dry from the heat after the water is all let out. The bread crumbs and other sediment from the dishes settle between the false and real bottom and is cleaned out after the washing is done. 90

What I claim, is:

1. In a dish-washer, a tub having a removable cover with a comparatively large central aperture, a skeleton frame resting on the bottom of the tub and having a portion projecting upward through said aperture, a rotary dasher or agitator in the frame, means on the projecting portion of the frame for rotating the agitator, a false bottom supported a short distance above the real bottom of the 100 tub and having circularly arranged slits for the dishes to stand edgewise in while being washed.

2. In a dish-washer, a tub having a removable cover with a comparatively large central aperture, a skeleton frame resting on the bottom of the tub and having a portion projecting upward through said aperture, a ro-

22

tary dasher or agitator in the frame, means on the projecting portion of the frame for rotating the agitator, a false bottom supported a short distance above the real bottom of the 5 tub and having circularly arranged slits for the dishes to stand edgewise in while being washed, said cover having notches adjacent its central aperture and said frame having

projections engaging in said notches and also below the cover, for the purposes set forth. 16

In testimony whereof I affix my signature, in presence of two witnesses.

JULIUS J. HOLLEY.

Witnesses:
